UNITED STATES PATENT OFFICE

MICHAEL C. THOM, OF CAREY, OHIO

FENCE BRACKET

Application filed March 12, 1930. Serial No. 435,233.

This invention relates to a bracket for use in connection with wire fences.

It is an object of the invention to provide a bracket which can be connected readily to a fence fabric and, when in position, can be used for holding barbed wires or the like adjacent to the top of the fence.

It is a further object to provide a bracket which is of simple construction, can be made at low cost, and can be made into a compact bundle for convenience in shipping and storing.

With the foregoing and other objections in view which will appear as the description 15 proceeds, the invention resides in the combination and arrangement of parts and in the details of construction hereinafter described and claimed, it being understood that changes in the precise embodiment of the invention 20 herein described may be made within the scope of what is claimed without departing from the spirit of the invention.

In the accompanying drawing the preferred form of the invention has been shown.

25 In said drawing

Figure 1 is a side elevation of the bracket supported in engagement with a fence fabric.

Figure 2 is a front elevation thereof.

Figure 3 is an enlarged section on line 30 3-3, Figure 1.

Referring to the figures by characters of reference, 1 designates an elongated flat strip of metal the end portions of which are twisted as at 2 to provide terminal tongues 3 and 35 4 which are disposed in a plane extending at right angles to the flat side faces of the strip 1. Each tongue is formed with longitudinal slits 5 extending thereinto from its free end to form a fork 6 and a bendable offset finger 7. Adjacent to the tongue 3 is provided a series of apertures 8.

Another elongated flat metal strip 9 forms the brace portion of the bracket and has one end portion twisted as at 10 to form a tongue

45 11. This tongue, like the tongues 3 and 4, has slits 12 extending thereinto from its free end to divide the tongue into a fork 13 and an offset bendable finger 14. The other end of the strip 9 is formed with slits 15 extending 50 thereinto from its free end and the material

between these slits is offset as at 16 to provide a coupling finger 17.

Normally the strips 1 and 9 are disconnected and can be arranged parallel with each other so as to be conveniently packed. When it is desired to use the bracket the tongue 4 is inserted under one of the strands of a wire fence F so that the finger 7 offset from said tongue will extend over the wire strand as shown in Figure 1 wherein the 60 strand has been indicated at S. Thereafter the coupling finger 17 is inserted into one of the openings 8 so that the strips 1 and 9 lap and are held close together. The tongue 11 is placed over one of the lower strands of the fence so that the finger 14 will extend under the strand. Fingers 7 and 14 are then bent into position with their free ends seated in the forked ends of the tongues so that the strips 1 and 9 are thereby fastened securely 70 to the fence.

The strand of wire to be supported by the bracket which has been indicated at s is placed on the tongue 3 and the finger 7 is then bent downwardly to straddle it and 75 hold it against lateral withdrawal from the tongue 3 supporting it. If another strand s' is to be supported by the bracket it can be extended over strip 1 and through the space from which the finger 17 has been struck. 80 The sides of the slit portion of strip 9 can then be drawn together so as to retain strand s' as shown in Figure 1.

It will be noted from the foregoing that it is possible to securely support strands of 85 barbed wire adjacent to the top of a fence and by raising or lowering the lower end of strip 9 so that it will engage a higher or a lower strand of the fence, the strip 1 can be supported at any desired angle relative to 90 the fence with the strands s and s' located either above or below the level of the top of the fence.

What is claimed is:

1. A knock-down bracket for wire fences 95 including a wire supporting strip having a tongue at each end formed with longitudinal slits, a finger offset from each tongue between the slits, there being apertures within the strip between its ends, a brace strip having 100

- slits extending into the ends thereof, bendable fingers offset from each of said ends between the slits, one of said fingers being insertible through an aperture in the wire supporting strip for holding the two strips assembled, said brace strip being contractable at that end adjacent to the finger in the aperture to embrace and hold a wire supported by the apertured strip.
- 10 2. A knock-down bracket including an apertured strip for supporting spaced wires, means integral with the ends of said strip for respectively engaging a fence fabric and one of the supported wires, a brace strip, means integral with one end thereof for engaging a fence fabric, there being slits extending into the other end of the brace strip, an offset finger formed between the slits and insertible into one of the apertures to hold
- 15 the two strips in engagement, said slotted end of the brace strip being adapted to straddle one of the supported wires and to be contracted to hold the wire against displacement relative to the strips.
- 20 25 3. The combination with an apertured wire supporting strip and a brace strip, means on said strips for engaging a fence fabric, of a finger offset from one end of the brace strip insertible into one of the apertures to support the apertured strip, said finger being angular, there being a space formed in the brace strip by the displacement of the finger for the reception of the supported wire, opposed walls of said space
- 30 being contractable toward each other to confine the wire and hold the strips assembled.
- 35

In testimony that I claim the foregoing as my own, I have hereto affixed my signature.

MICHAEL C. THOM.
